FUEL PUMP

John H. Holloway, Green Bay, and Moyes J. Murphy, Milwaukee, Wis., assignors to Murphy Diesel Company, a corporation of Delaware

Application April 29, 1938, Serial No. 204,974

3 Claims. (Cl. 103—41)

The invention relates to fuel pumps.

The object of the invention is to provide improvements in the cut off construction of that type of fuel pump having a constant stroke but a variable cut off which is produced by a groove or scroll on the plunger registering with a relief port.

Heretofore the cut off scroll on the plunger has been of relatively large volume, and in some pumps having a vertically disposed plunger and a discharge valve at the lower end of the pump barrel it has been necessary to use two ports in order to properly fill the pump and free it of entrained air. The object of the present invention is to provide a cut off groove or scroll on the plunger of small width and depth so as to keep the volume of the pump chamber a minimum and just sufficient to handle the flow. Furthermore, the improved cut off groove acts to vent air from the pump barrel during the outward stroke of the plunger and also makes the pump self cleaning. Furthermore, the cut off of this invention acts to quickly reduce the pressure at the end of the effective stroke of the plunger. Also because of the small area of the groove there is a minimum of leakage and side thrust against the plunger.

A further object of the invention is to provide an inclined cut off groove on the plunger, the projection of whose inclined portion may be within the width of the relief port, so that the pump may be set to an idling position.

A further object of the invention is to provide a cut off relief on the plunger which is cheap and easy to make and easy to measure and hold its tolerances.

A further object of the invention is to provide a construction in which the plunger has a plurality of spaced cut off grooves which may be successively positioned adjacent one port or one of a plurality of ports as their control edges wear down, so that the life of the plunger may be markedly increased over that of the usual type and furthermore to provide for an equidistant spacing of communicating grooves on the plunger, so that the pressures on the same may be balanced.

The invention further consists in the several features hereinafter set forth and more particularly defined by claims at the conclusion hereof.

In the drawing:

Fig. 1 is a vertical sectional view through a pump embodying the invention taken along the line 1—1 of Fig. 2;

Fig. 2 is a detailed sectional view of pump

taken at substantially right angles to the line of Fig. 1;

Fig. 3 is a view similar to Fig. 2 showing the plunger in an intermediate position;

Fig. 4 is a detailed sectional view similar to Fig. 2 showing certain modifications;

Fig. 5 is a detailed sectional view taken on the line 5—5 of Fig. 4;

Fig. 6 is a detailed sectional view similar to Fig. 5 showing certain modifications;

Fig. 7 is a detailed sectional view similar to Fig. 5 showing certain modifications.

Referring to the drawing, we have shown a pump including a casing 4, a barrel 5 mounted in said casing, a valve seat member 6 mounted in the reduced end of said casing and clamped thereto by a sleeve nut 7 which also clamps a flanged nozzle member 8 against said member 6. The nozzle member has the spray orifices 9 and the stepped bores 10, 11, and 12 leading to said orifices.

A ball valve 13 is normally held against its seat in the member 6 at the end of the discharge passage 14 therein by means of a grooved pin 15 and a spring 16 holding said pin against said valve.

The barrel 5 is provided with a port 17 which forms an inlet and a relief port and is controlled by a plunger 18 working in the barrel 5, it being noted that when said plunger is at the inward end of its stroke said port 17 is uncovered so that fuel may flow freely into the barrel, it being noted that a partial vacuum may exist in the pump chamber under some conditions before the port 17 is uncovered.

As previously noted the pump is of the type having a constant stroke and variable cut off, the cut off being controlled by a scroll or relief on the plunger cooperating with a relief port. The plunger 18 has a shallow cut off groove 19 formed therein by grinding or milling and having straight end portions 20 and 21 and a spirally inclined portion 22 connecting said end portions. It will be noted from Fig. 2 that the pitch of the portion 22 is such that the displacement of the edge 23 of the end portion 20 of the groove from the edge 24 of the end portion 21 of said groove is less than the width of the port 17, so that when the plunger is in its idling position as shown in full in Fig. 2, some portion of the groove will at all times overlap the port 17 during the entire stroke of the plunger, so that fuel taken into the barrel will be by-passed back into the port 17 during the entire stroke of the plunger. If now the plunger 18 and the barrel 5 be ro-

tated relative to each other to bring the groove 19 to the dotted line position shown in Fig. 2, then the port 17 will not come into register with said groove until later in the stroke of the plunger, and thus by relative rotation between said barrel and plunger the port 17 comes into register with the groove 19 sooner or later, and more or less fuel is by-passed from the barrel 5, so that less or more fuel is delivered past the valve 13 to the spray openings 9 on the delivery stroke of the pump. In Fig. 3 we have shown the plunger turned to a position for half load where the port 17 traverses the groove 19 at about one-half the length of the inclined portion 22 of the groove.

It is further to be noted that the straight portion 21 always provides for a certain amount of relief near the end of the stroke of the plunger, and this provides for a definite release of high pressure from the barrel before the plunger finishes its stroke.

With the above form of cut off groove and its arrangement relative to the port 17 the volume of said groove is very small compared to the usual arrangements and may be just sufficient to handle the flow and keep the volume of the pump chamber to a minimum. The small volume of the cut off groove also reduces the chance for leakage since there is a greater area of plunger in contact with the barrel, and it also reduces the side thrust that may be produced by the fuel against the plunger. It has also been found that any air that may get into the chamber is forced into the groove on the outward stroke of the plunger and out of the groove during the registry of the straight portion 21, and is thus expelled from the pump chamber before admission of the fuel.

The modification shown in Figs. 4 to 6 consists in providing a plurality of spaced grooves 19' on the plunger 18', each similar to the groove 19 and preferably, but not necessarily equally spaced and connected together at their upper ends either by the communicating radial channels or holes 25 as shown in Figs. 4 and 5 or an exterior annular groove 26 connecting the upper end portions of the grooves 19'. With these modifications one of the grooves 19' is initially positioned, so that within the range of its angular adjustment it will cooperate with the port 17 in the barrel as in the first described construction, and under these conditions the other grooves 19' act as pressure balancing grooves and communicate with the first groove 19' and the port 17 to permit the expulsion of air through said port from all the grooves. Thereafter, when the edges of the groove 19' then registerable

with the port 17 wear down, the plunger may be turned to bring another of the grooved portions 19' into register with said port 17, and when the edges of this second grooved portion 5 wear down, the third grooved portion is brought into registry. Thus the multiplicity of grooves not only prolongs the active life of the plunger but also acts to balance the pressures on the plunger during the pumping stroke.

10 In the modification shown in Fig. 7 the barrel 5 is provided with spaced grooves 19'' similar to the grooves 19 and adapted to cooperate respectively or successively with ports 17'', so that after one set of registering grooves and ports 15 wear down, the position of the plunger may be changed to bring a different groove into register with a different port.

We desire it to be understood that this invention is not to be limited to any particular form 20 or arrangement of parts except in so far as such limitations are included in the claims.

What we claim as our invention is:

1. In a fuel pump, the combination of a barrel having a port for inlet and relief, and a second port angularly displaced with reference to the first named port, said second named port being 25 out of use when said first named port is in use, a plunger operating in said barrel, said plunger having a plurality of grooves communicating with the barrel and adapted to cooperate, one at a time, with either of said ports.

2. In a fuel pump, the combination of a barrel 30 provided with an inlet and relief port, a plunger working in said barrel and adapted to overrun said port, said plunger having a cut off groove 35 having straight end portions parallel to its axis and a helically inclined portion between said end portions, one of said end portions being communicable with the barrel ahead of the plunger, the circumferential displacement of said straight end portions relative to each other being such that the distance between the trailing edge of one of said end portions and the projected leading edge of the other of said end portions is less than the width of the port.

40 3. In a fuel pump, the combination of a barrel provided with an inlet and relief port, a plunger working in said barrel and adapted to overrun said port, said plunger having a cut off groove 45 having an inclined portion, the width and pitch of said groove being such that the circumferential displacement of the ends of the groove at opposite sides thereof is less than the width of the port.
